UNITED STATES PATENT OFFICE.

THEODORE P. FRANKE, OF BUFFALO, NEW YORK.

STEAM-GENERATOR.

SPECIFICATION forming part of Letters Patent No. 232,255, dated September 14, 1880.

Application filed January 28, 1880.

To all whom it may concern:

Be it known that I, THEODORE P. FRANKE, of Buffalo, in the county of Erie and State of New York, have invented a new Improvement 5 in Steam-Generators, of which the following is a specification.

Figure 1 is a perspective view of the device. Fig. 2 is a sectional front elevation of the device on line $x x$, Fig. 3. Fig. 3 is a sectional 10 side elevation of the device on line $y y$, Fig. 2. Fig. 4 is a partial front elevation of the device. Fig. 5 is a transverse sectional plan view on line $z z$, Fig. 3.

Similar letters of reference indicate corresponding parts.

This invention relates to that class of steam generators or heaters in which a multiplicity of water-tubes connect the drums or cylinders of the boiler.

20 This invention is an improvement upon the steam-generators for which a patent, No. 203,721, was granted to me May 14, 1878, and consists of a new combination or arrangement of cylinders and tubes in order to increase the 25 efficiency of the generator or heater.

In the drawings, A A represent two horizontal cylinders that serve as mud-drums, set parallel with each other and some distance apart, and connecting directly at their rear 30 ends with a like mud-drum, B, that is set at right angles to them.

C C are two steam and water cylinders, set close together parallel with the drums A A, and above them on either side of an imaginary

35 line extended upward from a point midway between the said drums. These mud-drums A A and cylinders C C are connected with each other by one or more rows of vertical inclined tubes, E E, and each drum A with a cylinder,

40 C, and their connecting-tubes E, is termed a side section of the generator or heater.

D is a cylinder, similar to the cylinders C C, set horizontally and above the drum B, and connects directly with the rear ends of the 45 cylinders C C, and at right angles to them.

This cylinder D and the drum B are connected with each other by one or more rows of perpendicular tubes, F, as shown, and this combination of cylinder D, drum B, and tubes F 50 is termed a transverse section.

The tubes G G, extending at an angle from the lower transverse drum, B, to the upper

front ends of the longitudinal horizontal cylinders C C, with which they are connected by the bent tube H, being located, as shown, beneath the cylinders C C and between the side sections of the generator, serve to prevent the flame in the fire-box from impinging upon the said cylinders C C and to deflect the flame upon and around the tubes E of the side sections. In place of these several tubes G G, one larger tube or pipe may be used to produce the same desirable effect.

The steam-dome K is set above the cylinder D and parallel with it, and is connected therewith by the tubes L L, and from the tops of the cylinders C C the tubes M M connect with the steam-dome K, to conduct the steam from the said cylinders C C to the dome K.

The manner of connecting the tubes and 70 cylinders in this steam generator or heater is similar to that set forth in Patent No. 211,901, granted to me February 4, 1879, wherein is described the construction of boiler-tubes and the manner of connecting them with the boiler 75 cylinders and drums.

The transverse drum and cylinder B D are preferably connected with the drums and cylinders A C by close wrought-iron pipe nipples, and other transverse sections, similar to the one 80 herein shown, may be connected to the rear of this one and with each other, to any desired number.

The grate-bars N are placed on a level with the bottoms of the longitudinal drums A A 85 and between them.

All the cylinders and drums are to be preferably furnished with separate risers for each and every tube, and the sockets in the cylinders or drums for the tubes are intended to be 90 tapped for screw-threads.

The drawings represent a boiler of about one hundred and fifty horse-power capacity, and I propose to construct all large power boilers after the same design; but in the construction of small boilers for power or heating purposes I dispense with the steam-dome herein shown, and carry the upper cylinder of the transverse section above the upper cylinders of the side sections, and let it serve as 100 the steam-dome.

In the construction of small boilers or steam-generators I may also leave out the tube or tubes that extend, as shown, at an angle from

the lower drum of the transverse section to the front ends of the upper cylinders of the side sections, for in small boilers such deflecting-tubes will not be required to direct the 5 flames to the side sections; and I may adopt other construction without departing from the principle of my invention; but in all cases the relative positions of the side and transverse sections will be the same, though the 10 number of connecting-tubes will be determined by the size of the generator and the purposes for which it is designed.

In boilers constructed in this manner the heat and flame from the fire have access to 15 every part of it, and the circulation of water through it is constant and regular.

Having thus described my invention, what I claim as new, and desire to secure by Letters Patent, is—

In a steam-generator, the combination, with 20 the side sections composed of mud-drums A, connecting-tubes E, and steam-cylinders C, and transverse section composed of mud-drum B, connecting-tubes F, and steam-cylinders D, of the tubes H G M L and steam-dome K, substantially as herein shown, and for the purpose described.

THEODORE PAUL FRANKE.
